UNITED STATES PATENT OFFICE

OLOF ENOCH TROBECK, OF BERLIN, GERMANY, ASSIGNOR TO THE NATIONAL ACME COMPANY, OF CLEVELAND, OHIO, A CORPORATION OF OHIO

MULTIPLE SPINDLE METAL WORKING MACHINE

Application filed February 25, 1931, Serial No. 518,045, and in Germany November 1, 1930.

This invention relates to multiple spindle metal working machines, more particularly to the frame thereof, the object of the invention being to provide an improved open frame 5 rigid in construction for the support of the work spindle carrier, sliding tool carrier and their operating mechanisms so constructed that the chips from the work carried by the spindles during the operation of the tools thereon will fall uninterruptedly into a pan located at the base of the machine. In multiple spindle machines, as usually constructed, the frame and the working parts very materially interfere with the tooling of 15 the machine and the effective operation of the machine in that they interfere with the uninterrupted flow of the chips from the work and consequently often retard the production of the machine. 20 The capacity of automatic multiple spindle screw machines has been very materially increased by reason of the increased speed of the tools and the high speed of the cuts made thereby and the employment of high grade 25 steel, all resulting in a considerably larger quantity of chips from the work and, therefore, anything that interferes with the falling thereof into the pan helps to retard the production of the machine, increases the difficulty 30 of removing the chips and prevents the continuous operation of the machine and consequently it is necessary in the ordinary running of the machines that the operator continuously remove the chips and turnings to 35 prevent breakage of the parts or interference with the work.

Therefore, the object of the present invention is the provision of an improved frame 40 having means particularly adapted to facilitate the lodgement of the chips and turnings in the pan and which means also increases the rigidity of the frame without in any way interfering with the accessibility of the tools.

45 In the drawing accompanying and forming a part of this specification—Figure 1 is a front view of the machine;

Fig. 2 is a cross sectional view taken on line 2—2, Fig. 1; and

50 Fig. 3 is a detail view illustrating a some-

what different way of securing the frame parts together.

Similar characters of reference indicate corresponding parts in the several views.

Before explaining in detail the present improvement and mode of operation thereof, I desire to have it understood that the invention is not limited to the details of construction and arrangement of parts which are illustrated in the accompanying drawing, since the invention is capable of other embodiments, and that the phraseology which I employ is for the purpose of description and not of limitation.

This improved frame in the preferred form 65 thereof shown comprises a suitable base having an oil pan *a* therearound. From this base two upwardly projecting standards *b* and *c* extend, each preferably of box formation 70 suitably spaced apart thus leaving the frame 75 practically open from side to side. The standard *b* supports the usual indexable work spindle carrier *g* having rotary work spindles *h'*, *h''*, *h'''* and *h''''* and the usual cross slide *k*, while the upright or standard *c* carries the 80 usual driving mechanism for the work spindles.

These two standards are shown connected together at their top by a tie member *d*. Extending from one standard to the other is a 85 hollow tube through which passes the rotary spindle driving shaft and on which tube is located a sliding tool carrier *i* which may have a guide arm guided by means carried by the tie member *d*.

For rigidly connecting the two standards or uprights *b* and *c* near their bases thereby giving rigidity to the frame, a roof shaped member *e* is located therebetween, and below the apex thereof and through the standards 90 a main cam shaft *m* passes whereby it is protected by the member *e* from the chips and turnings of the work.

This roof shaped member may be formed integral with the standards *b* and *c* if preferred or may be bolted thereto by screw bolts *f*, (Fig. 3), the integral formation being preferable in the smaller sizes of machines. By means of this roof shaped member 95 the chips and turnings from the work 100

spindles can drop and slide thereon and be deflected into the chip receiving and oil pan extending around the base of the machine, and dropping thereinto from both sides of 5 this member *e* which as hereinbefore stated very materially adds to the rigidity of the frame and does not in any way interfere with the accessibility to the tools and therefore, does not interfere with the tooling of the 10 machine.

The upper or apex portion of this member *e* is located directly under the spindle driving shaft and is therefore in position to properly deflect the chips and turnings falling from 15 the stock and thus prevents the lodgement and piling up of the chips where they would interfere with the proper operation and speed of the machine.

It is to be understood that by describing 20 in detail herein any particular form, structure or arrangement, it is not intended to limit the invention beyond the terms of the several claims or the requirements of the prior art.

25 Having thus explained the nature of my said invention and described a way of constructing and using the same, although without attempting to set forth all of the forms in which it may be made, or all of the modes 30 of its use, I claim:

1. A multiple spindle automatic machine having a base and a chip receiving pan, two upright standards secured to said base and spaced apart to provide an open sided frame 35 and adapted to carry an indexible work spindle carrier and its co-operating mechanisms, and a bracing roof formed member between said standards and below said work spindle and in position to deflect chips and 40 turnings from the work into the chip receiving pan.

2. A multiple spindle automatic machine having a base and a chip receiving pan located around the outside of the base, two upright standards secured to said base and spaced apart to provide an open sided frame and adapted to carry an indexible work spindle carrier and its co-operating mechanisms, and a bracing roof formed member 45 between said standards and below said work spindle and in position to deflect chips and turnings from the work into the chip receiving pan.

3. A multiple spindle automatic machine having a base and a chip receiving pan, two upright box formed standards secured to said base and spaced apart to provide an open sided frame and adapted to carry an indexible work spindle carrier and its co-operating mechanisms, and a bracing roof formed member 55 between said standards and below said work spindle and in position to deflect chips and turnings from the work into the chip receiving pan.

60 4. A multiple spindle automatic machine

having a base and a chip receiving pan, two upright standards secured to said base and spaced apart to provide an open sided frame and adapted to carry an indexible work spindle carrier and its co-operating mechanisms, 70 a tie member connecting the tops of said standards, and a bracing roof formed member between said standards and below said work spindle and in position to deflect chips and turnings from the work into the chip receiving pan. 75

5. A multiple spindle automatic machine having a base and a chip receiving pan, two upright standards secured to said base and spaced apart to provide an open sided frame 80 and adapted to carry an indexible work spindle carrier and its co-operating mechanisms including a sliding tool carrier and a tubular member for supporting it, a tie member connecting the tops of said standards, means between the sliding tool carrier and the tie member for guiding the tool carrier, and a bracing roof formed member between said standards and below said sliding tool carrier and in position to deflect the chips and turnings from the work into the chip receiving pan. 85

6. A multiple spindle automatic machine having a base and a chip receiving pan, two upright box formed standards secured to said base and spaced apart to provide an open sided frame and adapted to carry an indexible work spindle carrier and its co-operating mechanisms including a sliding tool carrier 90 and a tubular member for supporting it, a tie member connecting the tops of said standards, means between the sliding tool carrier and the tie member for guiding the tool carrier, and a bracing roof formed member between said standards and below said sliding tool carrier and in position to deflect the chips and turnings from the work into the chip receiving pan. 95

7. A multiple spindle automatic machine having a base and a chip receiving pan extending around the base, two upright box formed standards secured to said base and spaced apart to provide an open sided frame and adapted to carry an indexible work spindle carrier and its co-operating mechanisms 100 including a sliding tool carrier and a tubular member for supporting it, a tie member connecting the tops of said standards, means between the sliding tool carrier and the tie member for guiding the tool carrier, and a bracing roof formed member between said standards and below said sliding tool carrier and in position to deflect the chips and turnings from the work into the chip receiving pan. 105

8. A multiple spindle automatic machine having a base and a chip receiving pan, two upright standards secured to the base and spaced apart to provide an open sided frame 110 and adapted to carry an indexible work spin-

idle carrier and its co-operating mechanisms, and a bracing roof formed member between said standards and below said spindles and in position to deflect chips and turnings from the work into the chip receiving pan, said member being free of connection with any part of the machine or frame except the upright standards.

9. An automatic multiple spindle machine having a frame comprising a bed provided with a pair of spaced upright standards unconnected at their sides and within which space a reciprocating tool carrier is located in position to leave a clear opening below the tool carrier and from standard to standard, and a roof shaped member filling a part of said space below the tool carrier and connected at its ends with the standards to give rigidity to the framework and having its sides converging to the top and spaced below the tool carrier thereby to deflect the chips and turnings away from the operating mechanisms of the machine.

10. An automatic multiple spindle machine having a frame comprising a bed provided with a pair of spaced upright standards unconnected at their sides and beam connected at their top and within which space a reciprocating tool carrier is located in position to leave a clear opening below the tool carrier and from standard to standard, and a roof shaped member filling a part of said space below the tool carrier and connected at its ends with the standards to give rigidity to the framework and having its sides converging to the top and spaced below the tool carrier thereby to deflect the chips and turnings from the operating mechanisms of the machine.

11. An automatic multiple spindle machine having a frame comprising a bed provided with a pair of spaced upright box formed standards unconnected at their sides and beam connected at their top and within which space a reciprocating tool carrier is located in position to leave a clear opening below the tool carrier and from standard to standard, and a roof shaped member filling a part of said space below the tool carrier and connected at its ends with the standards to give rigidity to the framework and having its sides converging to the top and spaced below the tool carrier thereby to deflect the chips and turnings away from the operating mechanisms of the machine.

Signed at Berlin, Germany, this 21st day of January, 1931.

OLOF ENOCH TROBECK.
